DEEP SUBMERGENCE UNDERWATER VEHICLE

Willy A. Fiedler, Los Altos, Calif., assignor to Lockheed
Aircraft Corporation, Burbank, Calif.

Filed Feb. 13, 1964, Ser. No. 78,612

Term of patent 14 years

(Cl. D71—1)

FIG. 1

FIG. 2

FIG. 3

FIG. 4

FIGURE 1 is a perspective view of the deep submergence underwater vehicle constituting the invention, showing my new design;

FIGURE 2 is a top plan view thereof;

FIGURE 3 is a side elevational view thereof;

FIGURE 4 is a rear or stern view thereof.

I claim:

The ornamental design for a deep submergence underwater vehicle, as shown.
